UNITED STATES PATENT OFFICE.

JOHN S. WILLEY, OF NEW YORK, N. Y.

NECKTIE-HOLDER.

1,318,248.

Specification of Letters Patent.

Patented Oct. 7, 1919.

Application filed October 5, 1918. Serial No. 257,027.

To all whom it may concern:

Be it known that I, JOHN S. WILLEY, a citizen of the United States, and resident of New York, in the county of New York and 5 State of New York, have invented certain new and useful Improvements in Necktie-Holders, of which the following is a specification.

This invention relates to necktie holders 10 and its object is to provide a rotating arc-shaped tube at the upper side of a resilient frame and when the tie and holder are located in the collar of the wearer the frame is compressed and the tube will automatically 15 turn outward so that no bulge nor inconvenient strain is lodged against the neck or collar. The tube is carried by the free ends of the frame which work in and out of the tube as the frame is compressed or relaxed and while the tube rotates. The 20 holder may also be provided with means for forcing the tie outward and away from the chest of the wearer.

These and other details and objects of the 25 invention are more fully described in the following specification, set forth in the appended claims and illustrated in the accompanying drawings, wherein:

Figure 1 is a front view of a simple form 30 of the improved necktie holder partly in section and in its normal condition.

Fig. 2 is a plan view of the same.

Fig. 3 is a view similar to Fig. 1 but with the tube compressed as when in use.

Fig. 4 is a plan view of the same.

Fig. 5 is an end elevation.

Fig. 6 is a similar view with the holder and tube depressed.

Fig. 7 is a front view of a modified form 40 of holder with supporting yoke for the tie.

Fig. 8 is a side view of the same.

Fig. 9 is a similar view of the holder in use.

Figs. 10 and 11 are views similar to Fig. 45 3 but showing the tube in various degrees of depression.

A serious objection to the use of the wire frame necktie holder without free ends separable to meet every pressure is that its resiliency is limited and bound as a ring and the strain put upon it eventually meets with resistance and the collar is not only distorted but made uncomfortable for the wearer.

In order to eliminate this objectionable 55 feature the present invention comprises a single piece of wire with wings 10 extending

from each side of the lower depressed portion of the frame which has the loop 11 and each wing having return arms 12 from which project the wire ends 13, leaving the 60 whole structure free to yield in all directions to conform with the height of the collar folds or the tension of the tie held thereon.

The ends conform with an arc-shaped tube 14 and extend therein freely and the 65 latter may revolve on the ends 13 but normally the arc is upward with a center below the collar button.

The tie may be secured on the tube 14 as a four-in-hand or as a cravat tie, and when 70 the loop at 11 is placed on the collar button and the wings depressed so as to fit within the folds of the collar, the whole frame is under tension and the ends 13 are thrown downward, as in Figs. 3, 4, 10 and 11, and 75 where the tube 14 makes a quarter turn or more on the ends 13 and its center be on a horizontal line or above the horizontal. In Fig. 4 the tube is shown concentric with the neck, which is the preferred position but in 80 all cases where the tube is forced downward the ends leave the tube more or less to conform with the pressure put upon the device.

Considerable bulk and thickness follows the location of the tie on the tube and if the 85 same were a straight bar, a mass would result that would be very uncomfortable to the wearer, but as will be seen in Fig. 4 the concave nature of the tube removes this mass from the neck and no uncomfortable 90 effect results.

The resilient nature of the wings 10 and the arms 12 result in retaining the holder in the collar when the loop 11 is lodged on the collar button so there is no danger of the 95 tie becoming dislocated and the arc-shaped frame affords comfort to the wearer.

There are occasions where, such as in the use of a soft shirt and collar, there is no rigidity in the latter and the same becomes 100 distorted and uncomfortable. In this case the tie may be appropriately placed on the curved tube 14, as shown in Fig. 7 and the wings hung on hump hooks 15 attached to the band of the collar so that the erect shape 105 of same may be preserved.

In this latter view the holder is shown provided with a yoke 16 so hung by its oblique eyes 17 as to be canted outward, as shown in Figs. 8 and 9, and when the tie 110 is located on the holder, to retain the shape of the tie and throw it outward away from

the chest of the wearer, this yoke is given an inclined tension.

In the three latter views a loop 18 is formed by crossing the horizontal members 5 19 and bending them upward to engage and lock the button against dislocation.

The use of this device saves half of the material ordinarily used for ties and the tie may be of the usual type eliminating the 10 neck band, or an ordinary tie may be cut in two parts and each worn at different times on the holder. With this device the tie is not stretched, rumpled nor twisted and it may be properly formed and adjusted on a 15 pencil or rod and transferred to the tube in case the latter is used with or without the yoke, the ends 13 being removed from the tube 14 by the depression of the wings, and a new tube with a new tie inserted in the 20 frame.

In this way any number of ties may be kept in shape and simply have the tube 14 inserted when it is desired to wear any one.

The tie may also be adjusted on the tube 25 as to present a new section in the front fold and thus prevent wear in one spot, lengthening the life of the tie in the collar, and it need not be so adjusted as to be continually subject to wear in one spot by the stick pin 30 being taken in and out daily. Nor is the stick pin taken in or out where a tie is retained in form and slipped on or off the tube, but only when a new section is exposed or a new tie used.

35 As shown in Figs. 10 and 11 the pressure on the wings may be sufficient to cause the complete reversal of the tube 14 and the same is possible if sufficient strain is put on the tie while on the bar. In the latter view the 40 depression results in the withdrawal of the ends 13 to a considerable degree, as when used in a very low collar, but the tendency of the ends is to always return the tube to the position of Fig. 1 when released.

45 It is apparent that for a very low wide spreading collar or for a very high collar to be used with a cravat or bow tie, the

holder can be modified by having lower or higher wings in the adjustment of the tube to about the same height as the collar button. 50

It is obvious that the device may be otherwise modified or arranged without departing from the essential features above described or from the scope of the appended claims.

What I claim as new is:

55

1. In a neck tie holder, the combination of a resilient frame having wings at each side, the ends of the said wings terminating in a loop at the lower end of the frame and free ends at the upper part of the frame, and 60 a tube to receive the free ends and permit of play therein.

2. In a neck tie holder, the combination with 65 a frame having a loop at its lower end, of wings extending upward and outward from the same, arms extending inward and downward, ends to the arms and normally extending toward each other, and an arc-shaped tube loosely carried on the ends.

3. In a tie holder, the combination with 70 a resilient frame, of a lower loop carrying section, upwardly and outwardly extending wings, and return members normally extending toward each other and having an arc shaped tube loosely carried by the return 75 members and inclosing the ends of the same.

4. In a tie holder, the combination of a resilient frame comprising a lower end with a loop, lateral wings, return members with inward extensions, a tube loosely carried by 80 the extensions and housing the same, and a yoke held normally in an inclined position.

5. In a tie holder, the combination of a resilient frame, a loosely mounted bar adapted to be depressed, wings carrying the 85 same extremities to the wings inserted in the bar, and a yoke mounted adjacent the bar so as to normally incline the same outward at its lower end.

Signed at New York, in the county of 90 New York and State of New York, this 19th day of September, A. D. 1918.

JOHN S. WILLEY.
